BOTTLE

Vernon Thiers Hamman, Springfield, Ohio

Application March 2, 1953, Serial No. 23,846

Term of patent 14 years

(Cl. D58—9)

To all whom it may concern:

Be it known that I, Vernon Thiers Hamman, a citizen of the United States and a resident of Springfield, in the county of Clark and State of Ohio, have invented a new, original, and ornamental Design for a Bottle, of which the following is the specification, reference being had to the accompanying drawing, wherein:

Figure 1 is a front elevational view of a bottle, showing my new design;

Figure 2 is a rear elevational view;

Figure 3 is a right side elevational view;

Figure 4 is a left side elevational view; and

Figure 5 is a plan view.

The dominant feature of my design resides in the portions shown in full lines.

I claim:

The ornamental design for a bottle, substantially as shown and described.

VERNON THIERS HAMMAN.
